UNITED STATES PATENT OFFICE.

DOMINGO ESPAGNOL AND AGUSTIN ENRIQUE ESPAGNOL, OF BUENOS AIRES, ARGENTINA.

DESIGN FOR WRAPPING PAPER.

Application filed May 26, 1926. Serial No. 17,864. Term of patent 14 years.

To all whom it may concern:

Be it known that we, DOMINGO ESPAGNOL and AGUSTIN ENRIQUE ESPAGNOL, citizens of the Argentine Republic, whose post-office address is 456 Pringles Street, Buenos Aires, Argentine Republic, have invented a new, original, and ornamental Design for Wrapping Paper, of which the following is a specification, reference being had to the accompanying drawing, forming part thereof.

The figure is a plan view of the wrapping paper constituting the design.

We claim:

The ornamental design for wrapping paper as shown.

DOMINGO ESPAGNOL.
AGUSTIN ENRIQUE ESPAGNOL.
